UNITED STATES PATENT OFFICE.

JAY L. THOMPSON, OF HOOSICK FALLS, NEW YORK.

SPRING-WHEEL.

1,321,162.

Specification of Letters Patent. Patented Nov. 11, 1919.

Application filed December 9, 1918. Serial No. 265,883.

To all whom it may concern:

Be it known that I, JAY L. THOMPSON, a citizen of the United States, residing at Hoosick Falls, county of Rensselaer, and 5 State of New York, have invented certain new and useful Improvements in Spring-Wheels, of which the following is a specification.

Reference may be had to the accompanying drawings, and the reference characters marked thereon, which form a part of this specification. Similar characters refer to similar parts in the several figures therein.

This invention relates more particularly 15 to the type of spring-wheels having a flexible shoe with spring-mechanism inclosed by the shoe whereby the shoe is yieldingly held in expanded form.

The principal object of the invention is 20 to yieldingly support the tread-portion of the shoe, and to facilitate the application and removal of the shoe.

Other objects will appear in connection with the following description.

25 Figure 1 of the drawings is a view partly in side elevation and partly in central longitudinal section in a plane perpendicular to the axis, of a spring-wheel embodying my invention, showing the spring-mechanism in position to interiorly support the tread-portion of the shoe.

Fig. 2 is a similar view showing the spring-mechanism in position to facilitate the application and removal of the shoe.

30 Fig. 3 is a transverse section of the same taken on the broken line 3—3 in Fig. 1.

Fig. 4 is a plan view showing the manner in which the shoe-supporting plates interengage one another.

40 Fig. 5 is a view in perspective of the yoke-shaped washer which prevents rotation of the spring-bolster.

Fig. 6 is a cross section taken on the broken line 6—6 in Fig. 3.

45 Referring to the drawings wherein the invention is shown in preferred form, 1 is the felly, and 2 are the spokes, comprising part of the body of a wheel, such as an automobile wheel.

50 A shoe, 3, of flexible material which may be similar to the shoe of an ordinary pneumatic tire is removably mounted upon the felly.

I have shown a shoe of the Q. D. C. type

mounted upon the felly by means of a 55 grooved rim, 4, in the usual manner.

The tread-portion of the shoe is interiorly supported by means of a series of plates, 5, which engage one another by means of tongue-and-groove joints, as shown in Fig. 60 4, forming a substantially continuous support for the interior tread-portion of the shoe.

Each of said plates, 5, is provided with 65 interiorly projecting brackets, 6, formed by the offset ends of a bracket-plate, 7, which offset ends are secured to the respective shoe-supporting plates, 5, by means of rivets, 8.

Coil-springs, 9, are confined under compression between the brackets, 6, of neighboring plates, 5.

Each of the plates, 5, is yieldingly supported by means of a bowed-spring, 10, the ends of which are supported by a spring-bolster, 11, having a shank, 12, which extends through a substantially radial opening, 13, in the felly, 1, said bolster being capable of a rotative movement about the axis of the shank, 12.

The bolster, 11, is formed with slideway-grooves, 14, which receive the ends of the bowed-spring, 10, with freedom for sliding self-adjustment of the ends of the spring when under compression. This construction also prevents relative rotation between the 85 spring and its bolster.

The bowed-spring, 10, is pivotally connected with the bracket-plate, 7, by means of a spindle, 15, which extends outwardly through the hollow shank, 12, of the bolster, 11, its outwardly projecting portion being screw-threaded at 16.

Inward and outward movement of the spindle, 15, is thus accompanied by inward and outward movement of the bracket-plate, 7, and the shoe-supporting plate, 5, which movement is permitted by a yielding of the bowed-spring, 10.

The bowed-spring, 10, and its bolster, 11, normally extend transversely of the shoe, as 100 shown in Fig. 3, and the bolster is of a shape which conforms to the interior of the shoe and serves to support the shoe between the tread-portion of the shoe and the wheel-body; and at the same time the bolster when 105 in transverse position serves to lock the beaded edges, 17, of the shoe within the side grooves in the rim, 4.

The outer end 18 of the spindle, 15, is angular in form adapted to receive a wrench whereby said spindle can be rotatively moved.

5 The outer end of the shank, 12, of the bolster, 11, is screw-threaded to receive a nut, 19, whereby said bolster is secured in fixed relation to the felly, 1.

In use, a U-shaped washer, 20, is interposed between the nut, 19, and the felly, as shown in Figs. 1 and 3, with the arms, 21, of said washer forming a yoke which embraces the felly, as shown in Fig. 3.

This washer, 20, has a lug, 22, which engages a slot, 23, in the shank, 12, of the bolster, thereby preventing rotation of the bolster and serving to hold the same securely in a transverse position with respect to the shoe.

20 Before applying the shoe to the rim, the several spring-bolsters and bowed-springs are loosely mounted upon the felly in a plane at right angles to the axis of the wheel with the plates, 5, extending circumferentially of the wheel.

The U-shaped washers, 20, are removed from the shanks, 12, of the bolster and are turned at right angles to their normal position so that their arms, 21, bear upon the 30 inner surface of the felly, as shown in Fig. 2, with the several washers, 20, interposed between said felly and a nut, 24, fitting the screw-threaded end of the spindle, 15.

By screwing up the nut, 24, the spindle, 35 15, can be drawn toward the center of the wheel compressing the bowed-spring, 10, and drawing the connected plate, 5, also inwardly or toward the center of the wheel. When the plates, 5, have all been thus 40 drawn toward the center of the wheel, thereby reducing the circumference of the shoe-supporting surface formed by said plates, the shoe can be readily applied to the rim and the beaded edges of the shoe inserted 45 within the side grooves of the rim.

After the shoe has been thus applied to the rim, the nuts, 24, are unscrewed permitting the spindles, 15, and plates, 5, to be forced outwardly by the bowed-springs, 10, 50 into engagement with the interior of the tread-supporting portion of the shoe.

The several bolsters and springs supported thereby are then rotated to transverse position with respect to the shoe by means of 55 a wrench applied to the outer end, 18, of the spindle, 15, after which the U-shaped washer, 20, is removed from the position shown in Fig. 2, and replaced in the position shown in Fig. 1, and the nut, 19, is 60 screwed up to securely lock the yoke in its transverse position.

The nut, 24, may be carried upon the screw-threaded end of the spindle, 15, for convenience if desired.

65 When it is desired to remove the shoe, the

plates, 5, are drawn inwardly by means of the spindles, 15, in the manner above described, and the bowed-springs, 10, and bolsters, 11, are rotatively moved from their transverse position as above described.

In the use of the wheel, the tread-portion of the shoe is yieldingly supported by the plates, 5, which in turn are yieldingly supported by the respective bowed-springs, 10, and also by the coil-springs, 9, due to the 75 tendency to further compress the neighboring coil-springs, 9, when one of the plates, 5, is forced toward the center of the wheel, thus forcing said coil-springs inwardly to a position where the circumferential extent of the wheel is less than when said coil-springs are in normal position.

Rotation of the respective spring-bolsters may be facilitated should they fail to rotate readily by pushing the bolster slightly outward within the shoe.

90 The bolster, 11, is preferably caused to rotate in unison with the spindle, 15, by suitable engagement therewith as by means of an angular enlargement, 27, on the spindle which engages a slot, 28, in the bolster while permitting relative longitudinal movement between the spindle and the bolster.

What I claim as new and desire to secure by Letters Patent is—

95 1. In a spring-wheel and in combination, a wheel-body; a flexible shoe mounted upon the wheel-body; plates within the shoe adapted to interiorly support the tread-portion of the shoe; bowed-springs for yieldingly supporting said plates respectively; a spring-bolster for each of the bowed-springs permitting self-adjustment of the ends of the spring, said bolster and spring normally extending transversely of the shoe, and being rotatively movable from said transverse position to permit application and removal of the shoe.

100 2. In a spring-wheel and in combination, a wheel-body; a flexible shoe mounted upon the wheel-body; plates within the shoe adapted to interiorly support the tread-portion of the shoe; bowed-springs for yieldingly supporting said plates respectively; a spring-bolster for each of the bowed-springs provided with inwardly convergent slideway-grooves within which the ends of said bowed-spring are slidably seated, said bolster and spring normally extending transversely of the shoe, and being rotatively 105 movable from said transverse position to permit application and removal of the shoe.

110 3. In a spring-wheel and in combination, a wheel-body having a felly provided with substantially radial openings; a flexible shoe 115 mounted upon the wheel-body; plates within the shoe adapted to interiorly support the tread-portion of the shoe; bowed-springs for yieldingly supporting said plates respectively; a spring-bolster for each of the 120

125

bowed-springs permitting self-adjustment of the ends of the spring, said bolster and spring normally extending transversely of the shoe, and being rotatively movable from 5 said transverse position to permit application and removal of the shoe; and means extending through the respective openings in the felly for rotatively moving the respective spring-bolsters and bowed-springs.

10 4. In a spring-wheel and in combination, a wheel-body; a flexible shoe mounted upon the wheel-body; plates within the shoe adapted to interiorly support the tread-portion of the shoe; bowed-springs for 15 yieldingly supporting said plates respectively; a spring-bolster for each of the bowed-springs permitting self-adjustment of the ends of the spring, said bolster conforming to and interiorly supporting the 20 shoe between the tread-portion of the shoe and the wheel-body.

25 5. In a spring-wheel and in combination, a wheel-body; a flexible shoe mounted upon the wheel-body; plates within the shoe adapted to interiorly support the tread-portion of the shoe, and having inwardly extending brackets; bowed-springs for yieldingly supporting said plates respectively; a 30 spring-bolster for each of the bowed-springs permitting self-adjustment of the ends of the spring; and coil-springs confined under compression between the brackets on the neighboring shoe supporting plates.

35 6. In a spring-wheel and in combination, a wheel-body having a felly provided with substantially radial openings; a flexible shoe mounted upon the wheel-body; plates within the shoe adapted to interiorly support the tread-portion of the shoe; bowed-springs for

yieldingly supporting said plates respectively; a spring-bolster for each of the bowed-springs permitting self-adjustment of the ends of the spring, said bolster and spring normally extending transversely of the shoe and being rotatively movable in unison from 45 said transverse position to permit application and removal of the shoe; members extending through the respective openings in the felly in connection with the several bowed-springs and spring-bolster, whereby said 50 bowed-springs and spring-bolsters can be rotatively moved from said transverse position to permit application and removal of the shoe.

7. In a spring-wheel and in combination, 55 a wheel-body having a felly provided with substantially radial openings; a flexible shoe mounted upon the wheel-body; plates within the shoe adapted to interiorly support the tread-portion of the shoe; bowed-springs 60 for yieldingly supporting said plates respectively; a spring-bolster for each of the bowed-springs permitting self-adjustment of the ends of the spring, said bolster and spring normally extending transversely of 65 the shoe and said bolster having a shank extending through one of said openings in the felly whereby said bolster and its bowed-spring are rotatively mounted upon the felly within the shoe; and means extending 70 through said opening in the felly whereby said bolster and bowed-spring can be drawn toward the center of the wheel and rotatively moved out of transverse position to 75 permit application and removal of the shoe.

In testimony whereof, I have hereunto set my hand this 15th day of November, 1918.

JAY L. THOMPSON.
